SHOCK CARRIER

Vernon J. Koch, Andover, Iowa

Application January 28, 1936, Serial No. 61,225

3 Claims. (Cl. 294—120)

This invention relates to devices for lifting, transporting and re-setting shocks of corn, wheat or the like, and the object of the invention is to provide a very simple means whereby shocks may be lifted up and transported from one portion of a field to another or from one situation to another by two men.

Another object of the invention is to provide a device of this character which includes two supporting poles or equivalent elements having inwardly extending pins or rods whereby two men can insert these rods or pins into the shock and by taking hold of the two poles, carry the shock from one situation to another.

15 A further object is to provide a device of this character in which the shock will be resiliently held together.

My invention is illustrated in the accompanying drawing wherein:

20 Figure 1 is a top plan view of my shock carrier;

Figure 2 is a side elevation thereof;

Figure 3 is a section on the line 3—3 of Figure 1.

25 Referring to the drawing, 10 designates a rod or equivalent element preferably made of wood having handle portions 11 at its opposite ends. This rod is preferably about 5 feet long and made of hard wood. Riveted, bolted or otherwise attached to this rod is a slightly curved spring element 12, preferably of steel, which in actual practice will be about 32" long, about 1 1/4" in width and about 1/4" thick. This element 12 is bolted to the supporting rod or bar 10 by means of bolts 13. Extending from the concave side 30 of the element 12 are a plurality of steel rods or pins 14. These may be welded to the steel spring 12, bolted or attached thereto in any simple manner. There are preferably four of these inwardly projecting rods or pins 14, the

two rods disposed on each side of the center being approximately 14" long and the other rod slightly shorter.

5 In the use of this device, two of these rods 10 are used, two men take up the position between the ends of the two rods and grasp the handles 11 of the two rods and then push the pins or rods 14 inward into the shock. The rods 10 are pulled inward towards each other until the shock is held firmly between the two steel strips 14, and 10 when this has occurred, the two men may lift the shock and carry it to any desired position, set it down and slide the pins or rods 14 out of the shock.

15 This device may be used for lifting shocks or stocks of corn, wheat and the like, or may be also used for lifting and carrying masses of hay or hay in cocks.

What is claimed is:—

1. A shock carrier of the character described, 20 comprising two carrying poles, curved resilient strips each attached at its middle to one of said poles, and inwardly extending pointed rods attached to the concave face of the strip.

2. A shock carrier of the character described, 25 comprising two wooden poles having handles at their ends, a curved metallic resilient strip attached at its middle to each pole, the convex face of the strip being disposed toward the corresponding pole, and pointed rods extending inward from the strip and adapted to be inserted 30 in the shock to be carried.

3. A shock carrier of the character described, 35 comprising two carrying poles, resilient strips attached to the respective poles, and inwardly extending rods attached to the strips as and for the purpose set forth.

VERNON J. KOCH.
